THEODORE CLOUGH, OF DOBB'S FERRY, NEW YORK.

Letters Patent No. 83,462, dated October 27, 1868.

IMPROVEMENT IN LAMPS.

The Schedule referred to in these Letters Patent and making part of the same.

To all whom it may concern:

Be it known that I, THEODORE CLOUGH, of Dobb's Ferry, Greenburg, in the county of Westchester, New York, have invented certain new and useful Improvements in Lamps for Burning Hydrocarbon-Oils; and I do hereby declare that the following is a full and correct description thereof, reference being had to the accompanying drawings, and to the letters of reference thereon.

My invention relates to lamps wherein a gas-jet flame is produced in lamps that burn wicks, by means of a jet of air from a jet-pipe or nozzle similar to a bat-wing or fish-tail gas-burner, the jet of air under pressure being forced to mingle with the products of combustion from a surrounding wick, as in Letters Patent of the United States, granted to me, bearing date the 26th of November, 1867.

In that patent, a form of construction is described and shown, adapted to burn light Hydrocarbon-oils, and which will also burn the heavier oils, commonly called kerosene-oils.

But I have discovered that, in burning the heavier oils in said lamps, the wick becomes encrusted with solid matter arising from the combustion, and that such accumulations cause the lamp to smoke, unless trimmed oftener than is convenient in the use of lamps, and this defect I have remedied by the first part of my said invention, which consists in combining with the air-jet pipe, two wick-tubes, which may be flat at their lower ends, and also at the point of union with the lamp-cap, but which are curved, at the burning-point, in the form of segments of a circle, the two segments being placed opposite each other, with the jet-pipe between them, in the manner shown in the drawings, and so as to allow air to come in contact with the wicks at their side edges, the segments being separated a little from each other for that purpose.

I have found that by thus partially enclosing the air-jet pipe with the segmental wick-tubes, instead of completely surrounding it by an annular wick-tube, I am enabled to burn the heavy oils with a gas-flame from a wick, without accumulations of solid products of combustion, beyond what occur in ordinary lamps with chimneys burning such oils.

But more particularly to describe my invention, I will refer to the accompanying drawings, of which—

Figure 1 is a plan view of my improved lamp;

Figure 2, front elevation;

Figure 3, a vertical cross-section; and

Figure 4, a horizontal cross-section through the lamp-cap, showing the plan view of the wick-lifter.

The body of the lamp, *a*, is supported upon a hollow standard, *b*, provided with a shut-off cock, *c*, which regulates the supply of compressed air, which may be supplied to the lamp, from any suitable source of supply of air under pressure, by the flexible tube *d*, shown broken off in the drawings.

A pipe, *e*, carries the air from the standard up through the body of the lamp to a point above the filling-hole, and if a filling-tube is not used, the lamp must not be filled above the top of this pipe, it being necessary, in this form of construction, that the upper part of the lamp-reservoir should be filled with air under pressure, which passes up to the burning-point through the air-jet tube *f*, and issues therefrom through the bat-wing or fish-tail gas-burner aperture *g*, in contact with the flame of the wicks of the opposite wick-tubes, *h h*, which, as before described, are flat wick-tubes, bent in the form of a segment of a circle at the burning-point above the lamp-cap, and placed opposite to each other, at such distance from each other and from the air-jet tube, as not entirely or wholly to enclose it, but leaving a space between the two segmental wick-tubes for air to pass.

The wick-lifters do not differ from ordinary wick-lifters, except in being geared together, so that, by turning the button, *i*, fast to the end of the shaft *j*, the wicks of both wick-tubes are lifted or depressed, by reason of the cogged wick-lifters, *m m*, on the shafts *j* and *k* of the two wick-lifters being geared together, and placed between the two wick-tubes. A deflector, *n*, is placed around the burner, to steady the flame.

I have described what I consider the best mode of introducing compressed air to the lamp, viz, the introduction of it into the lamp-body; but it may be brought to the jet-pipe by any suitable conductor or conduit outside of the lamp-body, so long as the jet-pipe has a bat-wing, fish-tail, or other suitable gas-jet nozzle, placed between the segmental wick-tubes, in the manner described.

I claim as my invention and improvement in lamps for burning hydrocarbon-oils—

The two opposite segmental wick-tubes, in combination with the air-jet pipe, having a gas-burner nozzle, when arranged in combination, substantially as described.
